CHARLES H. DAVIS, OF NEW YORK, N. Y.

COMBINED TRAIN ARRESTING AND SIGNALING MECHANISM FOR ELECTRIC RAILWAYS.

SPECIFICATION forming part of Letters Patent No. 605,664, dated June 14, 1898.

Application filed November 9, 1897. Serial No. 657,926. (No model.)

To all whom it may concern:

Be it known that I, CHARLES H. DAVIS, of the city, county, and State of New York, have invented a new and useful Improvement in a Combined Train Arresting and Signaling Mechanism for Electric Railways, of which the following is a specification.

My invention relates to electric railways wherein there is an electric-motor vehicle and a line conductor wherefrom the motor of said vehicle derives its actuating-current.

My invention consists, first, in the improvement in the art of governing the movement of an electric-motor vehicle taking its actuating-current from a line conductor, as aforesaid, which consists in controlling the maintenance of electrical circuit between said motor and said conductor at a point on said conductor from a station distant from said point; also, in the combination of such a line conductor and electric-motor vehicle, as aforesaid, with a signal in proximity to said conductor, of means for actuating said signal and also for simultaneously controlling the closing and breaking of electrical circuit between said motor-vehicle and said conductor at a point distant from said signal; also, in the construction and arrangement of the circuit-breaking devices, of the combined circuit-breaking devices and signal, of the circuit-breaking devices in combination with mechanism for applying the brakes to the vehicle, together with the other combinations and instrumentalities hereinafter more particularly pointed out in the claims.

In the accompanying drawings, Figure 1 is a side elevation showing a signal apparatus in combination with means for breaking circuit between the third rail of the railway and the motor on the vehicle. Fig. 2 is an end elevation of the third rail and its support and of a car on the main line, showing the contact-arm between car and third rail and the operation of said contact-arm to actuate the brakes.

Similar letters of reference indicate like parts.

A represents the main railway-line.

B is a third rail elevated upon a support, as C, and extending parallel to the track A. The third rail B is, as usual, insulated from the ground.

D represents a car, and E the driving electric motor thereof.

F is an arm pivoted at G in the car and provided with a retracting-spring H, normally operating to press it in contact with the third rail B.

It will be understood, therefore, that under normal conditions, with the car traveling over the track, circuit proceeds from the third rail B, through the arm F, to the motor E, and so to the main track A and ground.

I is a signal-arm pivoted at the top of the post J and connected by a vertical rod K with one end of the bell-crank lever L. The other end of lever L is pivoted to the rod M, which extends below the third rail B. This rod M is pivoted to the lower ends of the pivot-levers N, the upper ends of which levers are all pivoted to a bar O, preferably having an upper inclined surface P.

Turning now to the contact-arm F, Fig. 2, this is connected by pivot-levers Q to the ordinary conductor's valve R of an air-brake system and so arranged that when said lever F is elevated into the position shown in dotted lines, Fig. 2, the said valve R will be opened to operate the air-brakes on the vehicle or train in the usual manner.

The operation of the whole device is as follows: Assuming the vehicle or train to be moving in the direction of the arrow 1, Fig. 1, let rod K, by any suitable means, be moved upward so as to bring the signal-arm I into the position I', dotted lines, this position being that indicating danger to the train approaching it. The elevation of the rod K then vibrates the bell-crank L, moving the rod M in the direction of the arrow 2, so turning the pivot-levers N and elevating the bar O, so that its inclined upper surface P rises above the level of the surface of the third rail, as indicated in dotted lines, Fig. 1. If then a vehicle provided with the arm F, as described, on coming up to the signal I and finding that signal set at "danger" I' does not stop, its arms F will run up on the elevated bar O and so be brought into the position shown in dotted lines in Fig. 2, thus breaking contact between the end of arm F and the third rail B and so breaking circuit through the motor E. The car would therefore stop on account of the cutting off of the source of energy; but

in addition to this, as already explained, the arm F in rising operates the conductor's valve R and so causes simultaneously the application of the brakes to the vehicle.

5. It is to be understood that I do not limit myself to any particular form of visual signal nor to any special means actuated by the contact-lever F for the purpose of insuring the application of the brakes.

10. I am aware that it is old to place stops beside the track of a steam-railway to cause a closing or breaking of an electrical circuit on the locomotive through which a bell or whistle or some other alarm mechanism is actuated, also that it is old to place beside a track a movable projection which when struck by the vehicle and brought back to normal position actuates a switch or signal or analogous devices. These contrivances have no relation to electric railways and do not belong to the present art.

15. I am also aware that it is old in electrical railways to provide a fixed stop in proximity to a track or conductor whereby a shoe or trolley is temporarily held out of contact with the conductor at certain definite places, such as crossings or other points where it is desired that there never shall be any electrical circuit between the motor and the line conductor, or, in other words, where it is always requisite that the current shall be broken.

20. The term "line conductor" as herein used means any conductor over which the current passes and from which it proceeds to the motor of the vehicle. The term "signal" means any kind of signal—visual, audible, or otherwise. The term "vehicle" does not necessarily mean one having wheels, but is used here simply as a convenient term to include 25 any sort of compartment, car, chamber, or carriage which contains any electric contrivance capable of setting it in motion when energized by a current received from a line conductor.

25. I claim—

1. The combination in an electric railway with a line conductor and an electric-motor vehicle receiving current therefrom through a traveling contact bearing on said conductor, of means for controlling the closing and

30. breaking of electrical circuit between said contact and said conductor from a station on the line, thereby permitting continued progress of said vehicle over, or causing its arrest 35 at, the point of circuit establishment and breakage, substantially as described.

2. The combination in an electric railway with a line conductor and signal in proximity thereto and an electric-motor vehicle receiving current from said conductor through a traveling contact bearing on said conductor, of means for actuating said signal and also 40 simultaneously controlling the closing and breaking of electrical circuit between said 45 contact and said conductor at a point distant from said signal, substantially as described.

3. The combination in an electric railway

with a line conductor and a movable guard device, of a signal located at a distance from said guard device, and means for actuating said signal and said guard device simultaneously; whereby when said signal is set in danger position said guard device is also placed in position to separate and so break electrical circuit between said line conductor and a body moving upon and along the surface of said conductor and meeting the said device, substantially as described.

4. The combination in an electric railway of a line conductor and an electric-motor vehicle, a contact-arm on said vehicle normally closing circuit between said vehicle-motor and said line conductor, and a brake mechanism on said vehicle controlled by said arm; the aforesaid parts being constructed and arranged so that when circuit is open between said contact-arm and said conductor said brake mechanism shall be controlled thereby to arrest the motion of said vehicle, substantially as described.

5. The combination in an electric railway of a line conductor and electric-motor vehicle, a movable arm on said vehicle normally closing circuit between said vehicle-motor and said line conductor, a stop movably secured in proximity to said conductor, a signal in proximity to said conductor and means for simultaneously actuating said signal in predetermined manner and also for adjusting said stop in position to cause said arm on meeting it to move out of contact with said conductor, substantially as described.

6. The combination in an electric railway of a line conductor and electric-motor vehicle, an arm on said vehicle normally closing circuit between said vehicle-motor and said line conductor, a movable cam in proximity to said conductor having its upper surface normally below the upper surface of said conductor, and means for actuating said cam to carry its upper surface above the upper surface of said conductor, and thereby causing said arm in moving over said cam to break electrical connection with said conductor, substantially as described.

7. The combination in an electric railway of a line conductor and electric-motor vehicle, an arm on said vehicle normally closing circuit between said motor-vehicle and said line conductor, a signal in proximity to said line conductor, a movable cam in proximity to said conductor having its upper surface normally below the upper surface of said conductor, and mechanism for simultaneously actuating said signal in a predetermined manner and also for actuating said cam to carry its upper surface above the upper surface of said conductor and thereby causing said arm in moving over said cam to break the electrical connection with said conductor, substantially as described.

8. The combination of a line conductor, an electromotor-vehicle, a movable arm on said vehicle normally making electrical contact

with said line conductor, a movable body in proximity to said conductor having its upper surface normally below the upper surface of said conductor, means for displacing said movable body so that it shall move said arm out of contact with said conductor, and a brake mechanism on said vehicle; the said brake mechanism being controlled by said arm when moved as aforesaid, to arrest the motion of 10 said vehicle, substantially as described.

9. The combination in an electric railway wherein current is taken from a charged conductor by a traveling contact thereon, of the conductor B, bar O having inclined surface 15 P, pivoted levers N supporting said bar, and rod M for actuating said levers, substantially as described.

10. The combination in an electric railway wherein current is taken from a charged conductor by a traveling contact thereon, of the conductor B, bar O, pivoted levers N supporting said bar, rod M actuating said levers, pivoted signal-arm I, rod K for moving said arm, and mechanism for transmitting the motion 20 of rod K to rod M, substantially as described.

11. The combination in an electric railway of a car, having a brake mechanism, a conductor's valve R controlling the same, a contact-arm F actuating said valve with conductor B along which said contact-arm F travels, 30 bar O supported in proximity to said conductor, and means for raising said bar to move said contact-arm out of contact with said conductor, substantially as described.

12. The combination in an electric railway 35 of a car, having a brake mechanism, a conductor's valve R controlling the same, a contact-arm F actuating said valve with conductor B along which said contact-arm F travels, bar O supported in proximity to said conductor 40 means for raising said bar to move said contact-arm out of contact with said conductor and a visual signal constructed to be exhibited in definite position by said means, substantially as described.
